UNITED STATES PATENT OFFICE.

HARVEY S. STONER AND BURTON STONER, OF MASSILLON, OHIO.

ACETYLENE-GAS GENERATOR.

No. 880,763.

Specification of Letters Patent.

Patented March 3, 1908.

Application filed June 7, 1907. Serial No. 377,714.

To all whom it may concern:

Be it known that we, HARVEY S. STONER and BURTON STONER, citizens of the United States of America, and residents of Massillon, 5 county of Stark, and State of Ohio, have invented certain new and useful Improvements in Acetylene-Gas Generators, of which the following is a specification.

This invention relates to improvements in 10 acetylene-gas generators, and it has for its chief object to provide a simple, efficient and comparatively inexpensive generator of that class in which the feeding of the calcium carbide is automatically controlled for generating gas as needed.

A further object is to provide a device of 15 the character mentioned in which a substantially uniform gas-pressure, or volume of gas, is maintained, resulting in an unusually steady light being provided.

A still further object is to provide an apparatus which, while it is particularly adapted for domestic lighting, is also applicable to lighting on a more extensive scale.

25 With these and other objects in view, the invention finally consists in the particular construction, arrangement and combination of parts which will hereinafter be fully described, reference being herein had to the 30 accompanying drawings, forming a part of this specification, in which—

Figure 1 is a side elevation of the invention; Fig. 2 is a vertical central section of the same; Fig. 3 is an enlarged detail sectional 35 view on the line 3—3, Fig. 1, showing the carbide-feeder partly in end elevation and partly in broken section; Figs. 4, 5 and 6 are sectional views respectively taken on the lines 4—4, 5—5 and 6—6, Fig. 1; Fig. 7 is a 40 detail perspective view of the feeder; Fig. 8 is a similar view of the free end of the lever, showing the safety-clip thereon; and—Fig. 9 is a perspective view of the adjustable guide.

Referring to said drawings, in which like 45 reference-numerals designate like parts throughout the several views—1 indicates the generator, 2 the carbide-holder, 3 the gasometer, and 4 the vertically-movable bell of the gasometer.

50 The carbide-holder 2, which is preferably rectangular in form, is mounted directly upon the top of the generator 1 and has its top normally closed by a gas-tight cap or cover 5. Rigidly mounted in the lower part 55 of said carbide-holder is a hopper 6 which terminates at its lower end in a horizontally-

directed discharge-mouth 7 which fits within a circular opening 8 provided in the side of a rotatable carbide-feeder 9, an annular collar 10 being fixed about the mouth of said hopper and serving as a bearing on which said feeder rotates. Said feeder, which normally stands in a substantially horizontal or non-discharging position parallel to one of the sides of the carbide-holder 2, is of tapered 60 horn-like formation, and is adapted, when slightly rotated forward, to discharge a portion of the carbide contained therein from its mouth 11 into the generator 1, an opening 12 being provided in the top of the latter. 65 A funnel-shaped tube 13, depending from the top of said generator and having its lower end submerged in the water contained in said generator, serves to direct the charge of carbide upon the top of an appropriately-supported cone 14 by means of which said charge is distributed. Said cone not only 70 serves as a distributor for the carbide, but, being of a relatively greater width at its bottom than the lower end of the tube 13, 75 also serves to effectually prevent gas-bubbles generated in the tank from rising into the carbide-holder through said tube, this latter being a most desirable feature since the collection of gas or moisture in the carbide-holder results in a deterioration of the carbide 80 contained therein.

The gas produced in the generator passes to the gasometer 3 through a connecting pipe 15 the discharge end of which is located 90 above the water level—that is, in the gas zone—of the gasometer.

The bell 4, which is vertically movable with respect to the tank-portion of the gasometer with the fluctuations in the gas-supply, has rigidly attached to its top the horizontal terminal 16 of a guide-arm 17 the body of which stands vertical and is parallel to the face of the gasometer, as shown in Figs. 1, 4, 5 and 6, and is guided in its movements as carried by said bell by the outwardly-extending prongs 18 of an adjustable guide 19, said prongs embracing opposite edges of said guide-arm. The guide 19 consists of a heavy wire loop, the parallel members 20 of which carry said prongs 18, and it is attached to the tank-portion of the gasometer by means of a bolt 21 which is projected outwardly between said members and has a securing-nut 22 thereon. 95

100 The guide-arm 17 is bent to form a yoke-like loop 23 at its upper end, and within said 105

110

loop is held the end of a lever 24 which is pivotally mounted at a point 25 intermediate its ends to a bar 26 and has its opposite end pivotally connected to a pitman 27 which latter is in turn pivotally connected to the end of a crank-arm 28 carried by a shaft 29. Said shaft is projected through the side of the carbid-holder, a suitable boxing, as 30, being provided therefor, and is rigidly attached to the feeder 9 on the side thereof opposite to the circular opening 8, said boxing 30 serving as a bearing for said feeder.

The lever 24, the free end of which is held within the loop 23 of the guide-arm 17, has no direct connection with said loop or with any part of the gasometer, but is normally held between the upper or cross member of said loop and a bolt or pin 31 projected across said loop, and is adapted to be carried in the upward movement of the bell 4 by said pin 31 and in its downward movement by said upper or cross member of said loop. The front end of said lever is therefore raised and lowered with the ascent and descent of said bell, and, through the intermediate mechanism, the feeder 9 is operated, being tipped downward into discharging position by the descent of the bell below a predetermined point and being again upraised to its normal position by the elevation of said bell.

As a means of preventing the disarrangement of the mechanism by the elevation of the free end of the lever beyond the point necessary to produce the complete tipping of the feeder 9, the bolt or pin 31 is so positioned that it will become disengaged from and slip by the end of the lever when the limit of its proper elevation is reached. In order to provide for the return of said bolt or pin 31 by the end of the lever after the former has been elevated above the latter, a clip or rocker 32 of clevis- or yoke-shape is pivoted at 33 to the end of said lever, said rocker projecting beyond the end of said lever, as is clearly shown in Figs. 4 and 8. The said bolt or pin in descending engages the projecting end of said clip, and the latter, swinging upon its pivot 33, is thereby tipped downward, as indicated in dotted lines in Fig. 8, allowing said bolt to pass thereby. The cross member of the loop 23 then engages the end of the lever, carrying the latter downward therewith. For preventing the swinging of the clip 32 upward out of alignment with the lever, a notch or notches 34 is or are provided in the under side or sides of the clip-member or members near the rear end thereof for the reception of a stud or studs 35 carried by said lever.

The bar 26, upon which the lever 24 is pivotally mounted, is stationary, being bolted at one end to a suitable bracket 36 carried by the carbid-holder 1 and at its opposite end to the tank-portion of the gasometer. A slight variation in the spacing apart of the

generator and the gasometer is admitted by the provision of a slot 37 in the gasometer-end of said bar 26. The bolt 21 on which the guide 19 is mounted serves as the securing-bolt for the end of said bar, the latter being held between the gasometer-wall and said guide.

The service-pipe 38 has its entrance end in the gas zone of the gasometer, as shown. As a means of eliminating any possibility of the bell 4 being elevated to a dangerous height with respect to the tank-portion of the gasometer, an escape-pipe 39 is provided, said pipe rising vertically into the gas zone of the gasometer and being embraced by a relatively larger pipe 40 which depends from the top of said bell to a point near the lower end of the latter. As is obvious, when the bell is elevated to a point where the lower end of said pipe 40 clears the water, the gas from said gas zone rushes outward to the atmosphere through said escape-pipe 39, thus immediately reducing the volume of gas and effecting a resultant lowering of the bell.

A water-bowl 41 is mounted on the side of the gasometer through which the latter is supplied with water, the opening into the tank being for an obvious reason located below the normal water-level. Provision is made for supplying the generator with water by mounting a pipe 42, having a funnel-shaped mouth 43, in the side thereof below its normal water-level. Said pipe 42 has a valve 44 therein by means of which said pipe is closed against the escape of the gas generated in said generator as it rises through the water.

An inclined false bottom 45 is preferably employed in the generator for directing the spent carbid to a point from which it may be readily drained off with the water through a valve or drain-cock 46.

From the foregoing it will be seen that a self-controlled acetylene generator is provided which is extremely simple in its construction and which has but few parts to become out of order.

It will be noted that various slight changes may be resorted to without sacrificing any of the advantages of this invention and without departing from the general spirit or scope of the appended claims. Hence we do not desire to be understood as limiting ourselves to the precise construction and arrangement of parts herein shown and described.

Having thus described our invention, what we claim as new, and desire to secure by Letters Patent, is—

1. In an acetylene generator, the combination of a carbid-holder, a generator and a gasometer, a feed device located within said carbid-holder, said device comprising a hopper, a rotatable feeder in open communication with the discharge-end of said hopper

and rotatable about said discharge-end, said feeder being of a tapered horn-like formation and normally standing in a non-discharging position, and means intermediate the movable member of said gasometer and said feeder whereby the partial rotation of the latter is effected, said means comprising a guide arm carried by said movable member, an adjustable guide for said arm, a stationary bar having one end mounted upon the carbide-holder and the other to a fixed part of the gasometer, a lever pivotally mounted upon said bar, one end of said lever carrying a pivoted clip and having connection with the movable member of the gasometer, and means intermediate the opposite end of said lever and the feeder whereby motion is communicated to the latter.

2. In an acetylene generator, the combination with a feeder and the movable bell of a gasometer, of a guide-arm carried by said bell, said arm being bent to form a loop at its upper end, a pivoted lever having one end loosely held within said loop, a pin projected across said loop for engaging and carrying said lever upward with the upward movement of said bell, said pin being positioned to disengage itself from said lever at a predetermined point in the upward movement, a clip carried by said lever, said clip being pivoted for admitting of the unobstructed descent thereby of said pin, and means intermediate said lever and said feeder whereby the movement of the latter to and from charge-discharging position is controlled by the movements of the former.

3. In a device of the character described, the combination with a feeder and a gasometer, of intervening mechanism whereby fluctuations in the volume of gas contained in said gasometer between predetermined points propels said feeder to and from charge-discharging position, said mechanism including a pivoted lever, a guide-arm carried by the movable member of said gasometer, a loop formed at the top of said guide-arm, a pin projected across said loop, said lever being normally held between said pin and the top of said loop and said pin being positioned to pass from under said lever at a predetermined point in the ascent of said movable member, and a pivoted clip carried by the end of said lever whereby the downward passage of said pin by the end of said lever is admitted, and an adjustable guide for said guide-arm.

45

40

predetermined point in the ascent of said movable member, and means whereby the passage of said pin by the end of said lever with the descent of said member is admitted.

4. In a device of the character described, the combination with a feeder and a gasometer, of intervening mechanism whereby fluctuations in the volume of gas contained in said gasometer between predetermined points propels said feeder to and from discharging position, said mechanism including a pivoted lever, a guide-arm carried by the movable member of said gasometer, a loop formed at the top of said guide-arm, a pin projected across said loop, said lever being normally held between said pin and the top of said loop, and said pin being positioned to pass from under said lever at a predetermined point in the ascent of said movable member, and a pivoted clip carried by the end of said lever whereby the downward passage of said pin by the end of said lever is admitted.

5. In a device of the character described, the combination with a feeder and a gasometer, of intervening mechanism whereby fluctuations in the volume of gas contained in the gasometer between predetermined points propels said feeder to and from charge-discharging position, said mechanism including a pivoted lever, a guide-arm carried by the movable member of said gasometer, a loop formed at the top of said guide-arm, a pin projected across said loop, said lever being normally held between said pin and the top of said loop, and said pin being positioned to pass from under said lever at a predetermined point in the ascent of said movable member, a pivoted clip carried by the end of said lever whereby the downward passage of said pin by the end of said lever is admitted, and an adjustable guide for said guide-arm.

In testimony whereof we affix our signatures in presence of two witnesses.
